FROZEN FOOD CUTTER

Clayton A. Laughlin, Minneapolis, Minn., assignor to
Arthur Salm, Inc., Chicago, Ill., a corporation of
Illinois

Filed May 2, 1966, Ser. No. 2,110

Term of patent 14 years

(Cl. D95—3)

FIG. 1 is a front elevation of a frozen food cutter, showing my new design; the opposite side is a mirror image of the side shown;

FIG. 2 is a bottom plan view thereof;

FIG. 3 is a top plan view thereof;

FIG. 4 is an elevation as seen from the left of FIG. 1; and

FIG. 5 is an elevation as seen from the right of FIG. 1.

The broken line illustration represents a uniform continuation of the cutter teeth.

I claim:

The ornamental design for a frozen food cutter, substantially as shown and described.
